B. KLEIN,
TOOL SHARPENING GAGE,
APPLICATION FILED JUNE 18, 1920

1,374,582.

Patented Apr. 12, 1921.

UNITED STATES PATENT OFFICE.

BENJAMIN KLEIN, OF CHICAGO, ILLINOIS.

TOOL-SHARPENING GAGE.

1,374,582.

Specification of Letters Patent. Patented Apr. 12, 1921.

Application filed June 18, 1920. Serial No. 389,822.

To all whom it may concern:

Be it known that I, BENJAMIN KLEIN, a citizen of the United States, residing at Chicago, in the county of Cook and State 5 of Illinois, have invented certain new and useful Improvements in Tool-Sharpener Gages, of which the following is a specification.

This invention relates to tool sharpening 10 gages.

It relates particularly to a gage for holding shears or other cutting tools at the proper angle to the abrading surface.

One of the objects of the invention is to 15 provide a gage by which the tool may be drawn over the abrading surface and which will maintain the tool at the proper angle to the abrading surface.

Other objects are to provide a gage which 20 is simple and inexpensive and into which the tool may be readily inserted.

The gage comprises, in general, a tool holder, preferably formed from a single 25 piece of metal, having jaws between which the tool is gripped and having a plane surface, for sliding contact with the abrading surface, whereby the tool is maintained at the proper angle regardless of the amount of abrasion.

30 Embodiments of the invention are shown in the accompanying drawings, wherein:—

Figure 1 is a perspective of one form of gage.

Fig. 2 is a top plan thereof.

35 Fig. 3 is a vertical longitudinal section.

Fig. 4 is a perspective of a modified form of gage.

Fig. 5 is a top plan of the modified gage, and

40 Fig. 6 is a vertical, longitudinal section thereof.

Figs. 1, 2 and 3 will first be described.

The gage is formed of a single strip of 45 spring metal, such as steel. The body of the strip is bent into a substantially U shaped loop having a flat top 10 and a similar, parallel flat bottom or base 11.

Top 10 serves as a handle for drawing the gage and the tool carried thereby along the 50 abrading surface 12, which may be a hone, strop or other device. Base 11 forms a plane surface for engaging the abrading surface. The base maintains the gage in a substantially vertical position relative to

the abrading surface and insures that the 55 proper relation is maintained between the abrading surface and the tool being sharpened.

The end of top 10 is bent downwardly to 60 form a jaw 13 and the end of base 11 is bent upwardly to form a jaw 14. Jaws 13 and 14 overlap to grip and hold a tool between them. The top and base of the gage are held properly separated and substantially parallel by a pin 15. Pin 15 is secured to base 11 and acts as a stop to prevent the outer jaw 13 from being depressed far enough to engage the abrading surface when pressure is applied to draw the gage and tool along the abrading surface in the 70 sharpening operation.

Inner jaw 14 is formed at such an angle to base 11 that, when a tool blade is clamped between the jaws with its flat side against jaw 14, the blade is held at the proper 75 sharpening angle relative to the abrading surface.

A blade of the tool to be sharpened, which is illustrated as being the blade of a pair of shears or scissors, is inserted between the 80 jaws from the top downward, as illustrated in Fig. 3. The dotted line shows the position of the blade before it is forced between the jaws. The full line shows the position of the blade between the jaws in sharpening 85 position against the abrading surface.

To use the gage, the blade of the tool to be sharpened is inserted between the top and base above the jaws as shown by the dotted lines of Fig. 3. With the base of 90 the gage resting on the abrading surface, the blade is then forced downwardly between the jaws until its sharpening angle or bevel engages the abrading surface, as shown by the full lines of Fig. 3. The 95 blade is now frictionally held at the proper sharpening angle by the resilient force of the jaws.

Using the top of the gage as a handle, the 100 base of the gage is drawn along the abrading surface in the direction of the arrows and, if desired, the blade of the tool may be drawn through the jaws in the direction of the arrow, while it is pressed to the abrading surface. The abrasion thus takes 105 place from the cutting edge of the tool toward the rear thereof and, if the blade is simultaneously drawn through the jaws, the

abrasion is diagonal relative to the cutting edge. Thus a good cutting edge may be produced.

Figs. 4 to 6 show a modified gage wherein 5 a single strip of metal is bent to form a base 20 for engaging the abrading surface 21. One end of base 20 is bent into a loop to form an inner jaw 22 and an outer jaw 23. Jaw 22 is at such an angle to base 20 that 10 the tool is held at the proper angle to the abrading surface by the resilient force of the jaws. A U-shaped handle 24 is secured to base 20 to be gripped by the operator for moving the gage and tool along the abrading 15 surface.

The blade of the tool is inserted and the gage is operated and functions in the same manner as previously described for the preferred form.

20 The gage provides a simple, cheap and easily operated tool holder. The base, engaging a considerable area of the abrading surface, provides a plane surface which always maintains the jaws and, consequently 25 the tool, at the same angle to the abrading surface. The wear of the tool, due to use and successive sharpening, does not affect or change the angle at which the tool is held and applied to the abrading surface. No 30 adjustments are necessary to obtain the proper angle. The blade is merely inserted with its flat side against the inner jaw, whereby it is always brought against the abrading surface at the same angle.

35 Having described my invention, what I claim as new and desire to secure by Letters Patent is:—

1. A tool sharpening gage comprising a single piece of metal bent to provide a pair 40 of tool holding jaws and a flat surface for sliding along and engaging only the top of an abrading surface and of sufficient area to invariably maintain a fixed angle between

the jaws and the abrading surface regardless of the extent of wear of the tool during 45 the sharpening process.

2. A tool sharpening gage formed from a single piece of metal which is bent into a loop to provide a plane surface for engaging the top of an abrading surface and a handle above the plane surface, the ends of the piece of metal being bent inwardly to overlap to form a pair of tool holding jaws which maintain the tool at a fixed angle to the plane surface. 55

3. A tool sharpening gage formed from a single piece of metal whose ends are bent toward each other and overlap to provide a pair of tool holding jaws, the intermediate body of metal being formed into a loop, 60 whose bottom provides a plane surface to be moved along the top of an abrading surface to maintain the jaws and surface at a fixed angle, and whose top provides a handle for operating the gage. 65

4. A tool sharpening gage comprising a pair of overlapping resilient jaws for holding a tool, the jaws being interconnected by a resilient loop shaped body providing a plane surface for engaging an abrading 70 surface and a handle for operating the gage, and a stop for preventing excessive compression of the loop.

5. A tool sharpening gage comprising a single piece of metal having its ends bent to 75 overlap to form a pair of tool holding jaws and the intermediate body bent into a loop to form a plane surface at a fixed angle to the jaws and for engaging and sliding along the abrading surface to maintain the jaws 80 and abrading surface at a fixed angle to each other during the relative movement therebetween to sharpen the tool.

In testimony whereof I hereunto subscribe my name.

BENJAMIN KLEIN.
